UNITED STATES PATENT OFFICE.

WILLIAM P. SLENSBY, OF BROOKLYN, NEW YORK.

THIMBLE.

SPECIFICATION forming part of Letters Patent No. 315,671, dated April 14, 1885.

Application filed August 16, 1884. (Model.)

To all whom it may concern:

Be it known that I, WILLIAM P. SLENSBY, of Brooklyn, county of Kings, and State of New York, have invented an Improvement in Thimbles, of which the following is a complete specification, reference being had to the accompanying drawings, in which—

Figure 1 is a side view of my improved thimble. Fig. 2 is a central vertical section 10 of the same on the line *c c*, Fig. 1. Fig. 3 is a horizontal section of the same on the line *d d*, Fig. 2. Fig. 4 is a perspective view thereof, and Fig. 5 is a detailed view of the thread cut by the same.

15 This invention relates to a thread-cutting attachment to a thimble; and it consists in forming the cutter out of the substance of the thimble by causing a tongue to project therefrom, said tongue being bent from the body of the 20 thimble, all as hereinafter more fully described.

In the drawings, the letter A represents a 25 suitable thimble. In one side of this thimble is formed, by a U-shaped or other incision, a tongue, B, the free end of which is bent outwardly, as shown in Figs. 2 and 3. By this 30 means cutting-edges are formed between the edges of the tongue B and the edges of the incision in the thimble itself from which the tongue was cut. Thus in Fig. 3 the cutting-edges are marked *a*, *b*, *e*, and *f*. The thimble 35 is used in the ordinary manner. When a thread is to be cut, it is simply inserted between the free end of the tongue B and the body of the thimble, and is thereby clamped by said tongue, so that a gentle pull on the thread will cause it to separate.

Inasmuch as the cutting of the thread is not

or need not be produced by drawing it along the cutting-edges, but by clamping it by means 40 of the tongue and then pulling it, the thread is not cut clean across, as it would be by shears or knife, but is dismembered in a tapering fashion, as is shown in Fig. 5, thereby leaving the thread in best form for insertion in the 45 eye of a needle. This saves a sewer much trouble in threading needles, and is a great advantage for that reason alone.

The invention is also of use because the cutter is at all times in convenient position, and 50 when used will tend to draw the thimble tight upon the finger, instead of tending to displace it, as is the case with cutters on thimbles that have heretofore been proposed.

What I mean by the "body of the thimble" 55 in this specification is the round body of metal which constitutes the thimble proper, or any round piece of metal which may be attached thereto, and from which the tongue B is made to project.

I do not broadly claim a thimble with a cutting attachment thereon, as such is not my invention; but

I do claim—

1. The thimble A, having the tongue B, 65 formed by an incision out of its round body, said tongue being bent outwardly to form the cutting-edges *a b* and *e f*, substantially as described.

2. The thimble A, combined with the cutting-tongue B, which is bent and formed out of the round body of the thimble, as specified.

WILLIAM P. SLENSBY.
